RESILIENT FOLDING RULE HINGE

Herman M. Gasstrom, Pelham, and John E. Gasstrom, Mount Vernon, N. Y., assignors to Eagle Rule Mfg. Corp., New York, N. Y.

Application September 13, 1951, Serial No. 246,408

5 Claims. (Cl. 33—119)

1

The present invention relates to hinges and pivoting means for folding rules and the like, and particularly to a resilient folding rule hinge.

The main object of this invention is to provide a hinge for a folding rule that is sufficiently resilient in its action to allow of easy opening and closing of the rule with a minimum of wear.

Another object of the invention is to provide a folding rule hinge that has a coil spring producing a desired amount of operative friction and ensuring proper locking of the rule in the fully open and closed positions.

A further object is to have such a folding rule hinge that is compact and not likely to get out of order and therefore durable.

It is also an object to produce a special resilient hinge for folding rule that is relatively simple and yet entirely practical in construction, while being reasonable in cost.

An important object is, of course to provide a resilient folding rule hinge of the character indicated that is not only effective in actual use by a workman, but completely avoids any increase in external dimensions over conventional hinges for the same purpose.

Other objects and the advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is an enlarged fragmentary elevation of a portion of a folding rule showing the mutually hinged portions of two rule sections extended in open position and joined by a resilient hinge made according to the present invention and embodying the same in a practical form;

Figure 2 is an exploded view of the same rule sections and the joint involved, with the rule portions in section and certain hinge portions in perspective view to clarify actual form and nature of the parts;

Figure 3 is an elevation similar to that of Figure 1 of the upper or left rule section in partly assembled condition;

Figure 4 is another elevation showing the other or opposite side of the same rule section appearing in Figure 3;

Figure 5 is an enlarged longitudinal section taken on line 5—5 in Figure 1 showing the rule sections initially assembled;

Figure 6 is a similar section of the same rule sections fully assembled and finished in construction and relation of parts; and

2

Figure 7 is a vertical section taken on line 7—7 in Figure 6.

Throughout the views, the same reference numerals indicate the same or like parts.

In folding rules, the hinge between sections is, of course an important feature of the rule involved, and especially is it important that the hinge offers no more than a minimum desirable amount of friction when the sections are to be opened or closed. Such rules should have a certain resilient resistance to being opened or closed that is just enough to cause them to give way when proper force is applied manually to open or close the sections, but should not require undue effort to do this nor any unreasonable strain that might break the rule.

Of course, more or less flat leaf springs have been enclosed in rule joints but they are limited in strength and likewise have certain disadvantages that it is desired to eliminate by a new principle of construction. Upon considering this problem, it has become apparent that it should be possible to introduce a coil spring of no more than a few turns into a folding rule joint in order to reap the benefit of the superior resilience of such a spring in opening and closing such a rule. As a result, a special resilient folding rule joint has been successfully produced that will be explained in full detail in the following.

Hence, according to the practice of this invention, and referring now again to the drawing, a folding rule, generally indicated at 8 primarily includes two rule sections 9 and 10, representing a large number of sections hinged together in a series to form a complete rule. Of the two sections shown, merely the end portions appear, with the ends 11 and 12 overlapping. Upon end portion 11 is secured a metal hinge or strike plate having longitudinal anchoring side flanges 13, 13, the plate itself being noted 14 and having a pair of aligned male locking projections 15, 15. The rule section 9 has a pair of short bevels 16, 16 along the edges of its end 11 with the flanges 13, 13 of plate 14 gripped upon these bevels to anchor the plate in position on the rule.

In similar fashion, a second hinge or strike plate 17 has a pair of anchoring side flanges 18, 18 along its edges gripping the bevels 19, 19 along the sides of rule section 10 at its end 12 to retain this section and plate assembled. This plate 17, however, in correspondence with the male projections 15, 15 has female seats 20, 20 into which the projections 15, 15 fit in extended open position or closed retracted position of the rule sections in more or less conventional manner.

In order to center the two plates and provide

hinge means, a downwardly projecting integral nipple 21 is formed on plate 14 and extends down into a corresponding hole 22 in plate 17, rule section 10 having a slightly smaller corresponding hole 23 through which nipple 21 extends to a short distance below the upper surface of this rule section so that the nipple engaging in the hole 22 of lower plate 17 will serve to accurately pivot the two plates with respect to each other. It may be well to note that the upper rule section 9 in its end portion 11 has an enlarged bore 24 concentric with nipple 21 for a purpose which will immediately be explained.

When the rule sections are assembled, a long grommet 25 having an upper head or retaining flange 26 extends down through hole 24 in section 9 and through nipple 21, lower plate 17 and hole 23 in lower section 10 and into a bottom finishing plate 27 having two anchoring teeth 28, 28 driven into the wood of section 10. In preliminary assembled condition as shown in Figures 2 and 5, the lower end of grommet 25 is simply straight as first introduced into the finishing plate, but when the parts are finished and finally locked into permanent association, the lower end of the grommet is upset or riveted over to form a bottom retaining flange or head 29 partly recessed into plate 27. The upper flange or head 26 fits loosely within hole 24 in the upper rule section, but serves a further purpose than merely to house the mentioned head 26.

Ordinarily, a more or less flat leaf spring is mounted within the rule joint in order to introduce a constant resilient friction between the hinge or strike plates tending to seat the male locking projections 15, 15 in the corresponding seats or recesses 20, 20. Such a leaf spring is sometimes rather stiff and may lose its power to retain the joint in stable open or closed condition, and the invention now involves the use of an entirely different form of spring.

Surrounding the upper portion of the grommet 25 beneath its head 26 is a coil spring 30 resting upon hinge or strike plate 14 of upper rule section 9, resiliently urging this plate down into a resilient frictional contact with lower plate 17 on rule section 10. The resilient reaction is provided by the grommet head 26 confining the upper end of the coil spring while the latter rests on plate 14 and this plate in turn rests on lower plate 17, and plate 17 rests on lower rule section 10 which is held with an upward bias by the bottom finishing plate 27 retained upon grommet 25 by its lower upset or riveted end 29. Thus the active parts are all retained between the upper and lower flanges or heads 26 and 29 of this grommet while spring 30 introduces the resilient factor therebetween.

The result is that upper plate is held with a given amount of pressure on lower plate 17 so as to ensure the seating of male projections in female seat portions 20, 20 in lower plate 17 in fully open and also in fully closed position of one rule section with respect to the other.

As the upper head 26 of the grommet if left exposed to view in clearance hole 24 of upper rule section would be unfinished and unsightly in appearance, a second upper finishing plate 31 is centered over hole 24 and secured in place by two anchoring teeth 32, 32 driven into the wood of upper rule section 9, thereby concealing the head 26 of the grommet as well as spring 30 and generally covering hole 24 and making the upper side of the joint as a whole resemble the lower side of this joint having the lower

finishing plate 27, the upper plate having a hole 33 to imitate the open lower end of the grommet and its lower finishing plate 27.

It has been stated that spring 30 is a coil spring, this including any true helix or frusto-conical form of spring, as desired.

If spring 30 in Figure 2 is closely scrutinized, it will be seen that it may be considered substantially frusto-conical in form as it is wider at the lower end than at the top. In any case, the spring occupies the hole 24 only and does not extend down into any portion of the lower rule section 10, being retained between hinge plate 14 and the upper flange 26 of grommet 25 beneath upper plate 31.

It is, of course obvious that we may make the rule sections of wood, plastic or light metal, while the hinge or strike plates may be made of brass, steel or any suitable metal or alloy, which is also true of the spring, grommet and finishing plates. Naturally, the dimensions and proportions of the parts may be altered to suit any special conditions and we are of course not limited as to materials or dimensions, but the principle remains, namely that the coil spring is included in the rule joint for introducing a particularly advantageous resilient effect allowing smooth opening and closing of the rule joint thus equipped. We may also make the rule involved of as few or of as many rule sections as may be desired, each joint being in form and construction similar to what has already been described hereabove.

Manifestly, variations may be resorted to, and parts and features may be modified or used without others within the scope of the appended claims.

Having now fully described our invention, we claim:

1. In a folding rule having a pair of rule sections and a pair of hinge or strike plates individually secured upon said rule sections with a male lock projection upon one plate and the other plate having a female seat portion therefor, the combination of a pivot nipple upon one plate, the other plate having a corresponding pivot hole into which the nipple projects and both rule sections having clearance holes concentric with said nipple, but the clearance hole in the rule section carrying the plate with the pivot nipple being greater in internal diameter than that of the other hole in the other rule section, a grommet extending down through the nipple and having a head upon one end within the greater hole, a coiled compression spring surrounding the grommet within the larger hole beneath the grommet head, a finishing plate mounted extremely of the relatively smaller hole with the grommet extending thru said finishing plate and being riveted over the latter upon the exterior thereof, and means fixed upon the rule section with the larger hole for covering the latter and concealing the grommet head and coil spring therein.

2. A resilient folding rule hinge according to claim 1, wherein the means for concealing the hole in which the grommet and coil spring are located includes a second finishing plate covering said hole and having anchoring teeth directed inward and driven into the material of the rule section upon which said plate is mounted, further anchoring teeth being directed inward from the finishing plate associated with the riveted end of the grommet into the material of the other rule section, the second finish-

ing plate corresponding to and resembling the said finishing plate associated with the riveted end of the grommet and centered with respect to said grommet.

3. A resilient folding rule hinge according to 5 claim 1, wherein the coil spring is substantially helical in form.

4. A resilient folding rule hinge according to claim 1, wherein the spring is substantially frusto-conical in form.

5. A resilient folding rule hinge according to claim 1, wherein the coil spring and the grommet head are located in the hole of one rule section and the nipple of the strike plate of said rule is directed away from the spring into the 10 hole in the other strike plate and rule section in a direction opposite to said spring, the spring

resting upon the first mentioned strike plate carrying said nipple and being located exclusively in the greater hole of the two holes in which the grommet is located.
